US00D620587S

(12) **United States Design Patent**
Reyniers

(10) **Patent No.:** **US D620,587 S**
(45) **Date of Patent:** **** Jul. 27, 2010**

(54) **SQUEEZE BULB**

(76) Inventor: **Lance A. Reyniers, 7754 N. Delta Pl., Milwaukee, WI (US) 53223**

(**) Term: **14 Years**

(21) Appl. No.: **29/299,754**

(22) Filed: **Jan. 3, 2008**

(51) **LOC (9) Cl. 23-99**

(52) **U.S. Cl. D23/499**

(58) **Field of Classification Search** D23/499, D23/210, 231, 316; D15/8; D24/108, 112, D24/127; D30/106; 92/92; 137/123, 142, 137/143, 150, 150.5, 151, 231; 210/167.21-167.27, 210/216.2; 417/181, 474, 478; 604/37, 212, 604/217, 911

See application file for complete search history.

(57) **CLAIM**

We claim the ornamental design for a squeeze bulb, as shown and described.

DESCRIPTION

FIG. 1 is a perspective view of a squeeze bulb embodying the invention;

FIG. 2 is a side view of the squeeze bulb of FIG. 1; and, FIG. 3 is a rear view of the squeeze bulb of FIG. 1.

The broken lines in FIGS. 1-3 represent unclaimed environmental subject matter.
